UNITED STATES PATENT OFFICE.

GEORGE M. HOPKINS, OF BROOKLYN, NEW YORK.

ELECTRO-MAGNETIC ANNUNCIATOR.

SPECIFICATION forming part of Letters Patent No. 240,717, dated April 26, 1881.

Application filed January 31, 1881. (Model.)

To all whom it may concern:

Be it known that I, GEORGE M. HOPKINS, of Brooklyn, in the county of Kings and State of New York, have invented a new and useful Improvement in Electro-Magnetic Annunciators, of which the following is a specification, reference being had to the accompanying drawings.

Figures 1 and 2 are respectively side and end elevations of the electric annunciator arranged for an open-circuit line. Fig. 3 is an electric annunciator arranged for a closed circuit, and Figs. 4 and 5 are side and end elevations of a modified form of the escapement.

My invention relates to annunciators for telephone and burglar-alarm lines, and for other analogous purposes; and it consists in an escapement operated by an electro-magnet, in combination with a series of superposed drops operated either by gravity or by springs, the escapement and drops being relatively arranged so that the drops will be liberated one after another in rotation by the movement of the escapement.

This annunciator will be employed to indicate to the central telephone-station the wants of the subscriber. For example, the first drop may indicate that telephonic communication is desired, the second that a messenger is wanted, while a third may be used to call the police, and the fourth to indicate fire. Any other arrangement of calls may be used in connection with the annunciator. When used in connection with a burglar-alarm it will indicate the room into which entrance is being made. It has a further application in connection with club telephone-lines, where it is desirable to call any particular person on the line. In the latter case a bell will be used in connection with the annunciator to make an audible signal.

Referring to Fig. 1, in which an annunciator for an open circuit is represented, the magnet A in the line over which the signal is sent is mounted on a right-angled frame, B, to the front face of which are hinged the several drops *a b c*, all turning on the same pivot, *d*, and all held in an inclined position by a catch, C, pressed by a spring, *e*, into an engagement with pins *ff'* projecting from the edges of the drops *a b c*.

Below the catch C and pins *ff'* a lever, D, is

pivoted to an arm projecting from the back of the vertical portion of the frame B. The outer end of the lever D carries a chisel-edged detent, *g*, whose edge is located below the space 55 between the pins *f* of the first and second drops, *a b*. The inner end of the lever D supports an armature, *h*, over the poles of the magnet A, and within its influence. The motion of the lever D is limited by the mortise in the frame 60 B, through which it passes, and the lever is kept by a spring, *i*, in its normal position—that is, with the detent *g* below the pins *f* and the armature *h* removed from the poles of the magnet.

The circuit in which the magnet A is placed is provided with a suitable number of battery elements, and with a simple push-button or key capable of closing the circuit when pressed. By closing the electrical circuit, including the 70 magnet A, the armature *h* is drawn down and the detent *g* is forced upward between the first and second pins *f*, raising the catch C, so as to liberate the first pin *f* belonging to the drop *a*, when the drop falls. Upon breaking the 75 circuit the lever D and catch C regain their normal position, and the pin *f* of the second drop, *b*, falls forward against the nib of the catch, and will be liberated when the circuit is again closed, repeating the operation just 80 described in connection with the first drop. In this manner any number of a series of drops may be liberated in succession. The drops are returned to their original position by raising them until the pins *f* are engaged by the 85 catch C, as shown in Fig. 1.

To adapt the escapement to a magnet in a closed circuit it is only necessary to place the magnet A above the armature *h*, as shown in Fig. 3, and to extend the spring *i* beyond the 90 pivot of the lever D. In this case the offices of the spring and magnet will be reversed. The magnet A will hold the lever in its normal position, while the spring *i* will move the lever D when the armature *h* is released by 95 the magnet. In this case the push-button or key by means of which the signal is sent will operate to break the circuit when pressed.

The escapement shown in Figs. 4 and 5 is the same in principle as that shown in the 100 other figures, but the construction is modified. In this case the catch C' is secured to the frame

B, and moves when the lever D' is moved, but is capable of moving independently when the drops are restored to their normal position. The lever D' carries a detent, g', which projects from its side, and is bent twice at right angles, so that the chisel-edge g² of the detent g' is in the same position relative to the pins f as in the arrangement shown in Figs. 1, 2, and 3. When the catch C' is raised by the action of the electro-magnet, the first pin f escapes, while the remaining ones are retained by the detent g', and when the lever D' is returned to its normal position by the spring i the second pin f will be released by the detent g' and drop forward against the catch C'. A second movement of the lever D' releases the second pin f in the same manner as the first was released. The drops are returned to their original position by placing the pins f in engagement with the catch C', as in the other cases.

When it is desired to give an audible signal to one person on a line and not to the others, all of the pins excepting the one attached to the drop indicating the person requiring the audible alarm are made of insulating material, as indicated in black in the drawings; but the particular drop indicating the person requiring an alarm is provided with a metallic pin, f', capable of making electrical contact with the catch C. In this case the catch C is insulated from other parts of the annunciator, and is included in an electrical circuit which

also includes the drop having the metallic pin f', also a battery and a vibratory electric bell 35 of ordinary construction, excepting that its rate of vibration is made very slow.

The pins f of insulating material, when brought into contact with the catch C, do not affect the local circuit; but when the metallic pin f' comes into contact with the catch C the local circuit is closed, and if this pin is instantly released no audible alarm is given, as the slowly-vibrating electrical bell has not been allowed sufficient time to operate; but if 45 the metallic pin f' is allowed to remain in contact with the catch C any considerable length of time the bell will give the alarm.

Having thus described my invention, what I claim as new, and desire to secure by Letters 50 Patent, is—

1. In an electro-magnetic annunciator, a series of superposed drops having one of their number fitted to close a local circuit, in combination with an escapement adapted to release one drop after another in succession, as herein specified. 55

2. In an electrical annunciator, the combination of the electrically-operated detent g, the catch C, and a number of superposed drops, 60 a b c, having escapement-pins f, as herein specified.
